UNITED STATES PATENT OFFICE

2,004,603

GAUGE PLATE CONSTRUCTION

Joseph Folk, La Porte, Ind., assignor to U. S.
Slicing Machine Company, La Porte, Ind., a
corporation of Indiana

Application October 11, 1932, Serial No. 637,246

18 Claims. (Cl. 146—102)

The present invention relates to slicing machines and one of the objects of this invention is to provide a gauge plate which gauges the thickness of the slices to be cut and is so mounted as to be movable out of operative position to a position in which the same may be readily cleaned. More specifically, this mounting is such that the ordinary adjusting knob which is used to adjust the position of the gauge plate for various slice thicknesses can be also used to move the gauge plate to an inoperative position clear of the knife to permit cleaning thereof.

Another object of this invention resides in providing means for mounting the gauge plate in such a manner that there is no substantial interference with the movement of the slices onto the slice receiving plate. In order to accomplish this result, the gauge plate is so mounted that it does not overhang the slice receiving plate more than is necessary. The adjusting means for the gauge plate is also arranged on the same side of the cutting plane of the knife as the substance support.

Other objects of this invention will appear hereinafter as the description thereof proceeds, the novel features, arrangements and combinations being clearly set forth in the appended claims.

In the drawings:

Fig. 1 is a side elevational view of a slicing machine provided with a gauge plate constructed according to this invention.

Fig. 2 is a front elevational view thereof;

Fig. 3 is a section taken substantially along the line 3—3 of Fig. 2;

Fig. 4 is a section taken substantially along the line 4—4 of Fig. 2;

Fig. 5 is a section taken substantially along the line 5—5 of Fig. 4; and

Fig. 6 is a section taken along the line 6—6 of Fig. 2.

In the drawings, reference numeral 10 represents the base of a slicing machine and 11 a knife bracket provided with a bearing 12 for the spindle of a slicing knife 13. The slicing knife is driven by means of gearing within the knife bracket 11 actuated by a motor within the raised portion 14 on the base 10. The carriage 15 provided with a handle 16 is reciprocated on guides 17 and 18 for movement in a plane parallel to the cutting plane of the knife 13. A suitable clamp 19 is slidably mounted on the guides 20 for movement toward and from the cutting plane of the knife and is provided with

prongs 21 on the forward face thereof and additional prongs 22 on the lower face thereof either of which of said prongs can be brought into engagement with the substance. The prongs 21 are adapted to engage the rear end of the substance for feeding short ends of the substance toward the cutting plane of the knife, and the prongs 22 are adapted to engage the top of the substance for feeding the same toward the cutting plane of the knife. The guides 20 are connected to a bearing 23 which slides on a rod 24 beneath the substance supporting surface of the carriage 15 so that the guides 20 and clamp 19 can be fed toward the cutting plane of the knife. A spring 25 engages the bearing 23 and urges the same in a direction toward the cutting plane of the knife against the gauge plate which will hereinafter be described. This part of my invention is described more in detail in my co-pending application, Serial No. 633,594 filed on the 17th day of September, 1932. As far as the present invention is concerned, the clamp may be fed forward manually as by means of an operating handle such as 26.

The carriage is manually reciprocated and a pressure, whether manual or spring pressure, is applied to the clamp 19 in the direction toward the cutting plane of the knife to feed the same against the gauge plate 27, the slice engaging surface 28 of which is adapted to be positioned the desired distance from the cutting plane of the knife 13 so that when the carriage 15 is moved past the knife, a slice of predetermined thickness is formed. As is most clearly illustrated in Fig. 3, the gauge plate 27 has a rod 29 secured thereto by means of a cross-pin 30 and this rod 29 passes through suitable bearings 31 formed integrally with the base 10. A pin 32 is press-fitted into an opening in the base 10 and has a cylindrical head 33 thereon which is adapted to be received within the opening 34 formed in the gauge plate 27. Thus the gauge plate 27 can be moved toward and from the frame 15 with the rod 29 and the pin 32, acting as guides for guiding its movement.

The rod 29 is provided with a threaded portion 35 and a set-screw 36 has an unthreaded portion 37 extending into the thread of the threaded portion 35. The screw 36 extends through a feed-nut 38 which is arranged in a convenient position at one side of the base 10. The nut is provided with a band 39 which extends peripherally about the nut 38 and is provided with

suitable graduations as indicated clearly in Fig. 2. This band also covers the screw 36.

A spring 40 surrounds the rod 29 and has one end thereof abutting against the bearing 31 and the other end thereof abutting against a collar 41 which is secured to the rod 29 by a set-screw 42 which extends through the collar and into a recess 43 in the rod so that the collar 41 may have only a limited amount of 10 rotational movement toward the adjacent portion of the base as indicated in Fig. 6. A washer 45 arranged within the recess 46 in the nut 38 is secured to the end of the rod 29 by means of a screw 47 and prevents separation of the 15 nut from the rod 29.

The gauge plate is shown at its extreme left hand position in Fig. 3 and in this position is farthest from the cutting plane of the knife. Upon rotation of the nut 38 in a clockwise direction as viewed from the right in Fig. 3, the unthreaded portion 31 of the screw travels in the thread of the threaded portion 35 and moves the rod 29 to the right against the action of the spring 40. A suitable arrow or indicating 25 line 48 formed on the frame of the machine, as is most clearly illustrated in Fig. 2, cooperates with the annular graduated band 39 to indicate the distance which the gauge plate is from the cutting plane of the knife and the thickness 30 of the slice to be cut.

Adjacent the opening 34 on the gauge plate there is formed a ledge 49 above the head 33 on the pin 32 and this rests on the head 33 even after the head 33 is fully retracted from 35 the opening 34, the engaging surface of the ledge forming a continuation of the adjacent surface of the opening 34. Therefore, when the gauge plate is in the position shown in Fig. 3, and also in Figs. 4 and 5, the gauge plate 40 is still guided at two points but can have a counter-clockwise movement, as viewed in Fig. 4, about the axis of the rod 29 as a center, or in a clockwise direction as viewed in Fig. 1. The gauge plate can have approximately 90° 45 of movement and is limited in this movement by the set-screw 42 which comes into engagement with the portion 50 of the base 15 as indicated by the dotted line position of the set-screw 42 in Fig. 6. The full line position of 50 the set-screw 42 shown in Fig. 6 indicates the normal position thereof when the gauge plate is in operative position. While the gauge plate is in a position away from the cutting plane of the knife, the same may be cleaned without endangering the operator as would be the case if 55 the gauge plate had to be cleaned while in operative position.

Not only is the gauge plate movable to an inoperative position but it can be moved to this position merely by operating the nut 38. This is due to the fact that the washer 45 abuts against the bottom of the recess 46 when the gauge plate is in the position shown in Fig. 3 with the head 33 of the pin 32 free of the 60 opening 34. As the operator is moving the nut in a counter-clockwise direction as viewed from the right in Fig. 3 to move the gauge plate to its extreme left-hand position shown in that figure, the continued movement of the nut after 65 the gauge plate reaches the position shown in Fig. 3 causes the screw 36 to bind in the threaded portion 35 of the rod 29 and causes the rod to rotate with the nut 38. The gauge plate, therefore, can be completely retracted to an 70 inoperative position by one hand of the operator 75

and without the necessity of placing the other hand anywhere near the cutting plane of the knife. This movement is also caused by the same means which gauges the thickness of the slices. When it is desired to move the gauge 5 plate back into an operative position, a clockwise movement of the nut 38 will move the gauge plate into that position from an inoperative position since there is sufficient frictional force which prevents the rod 29 from moving 10 relative to the screw 37 while the gauge plate is being moved into operative position.

It also will be noted that the gauge plate does not form any material obstruction on the side of the slicing knife to which the slices are 15 deflected as the machine is operated. The operator, therefore, can reach in past the gauge plate and catch the slices as they are deflected by means of the deflector 51 and deposit them on a slice receiving tray 52 carried by a bracket 20 53. Since the operator is standing at the front of the machine where he can operate the carriage 15 with one hand, it is very highly desirable that his view of the slice as it is being deflected be not obstructed by the gauge plate for 25 if his view is obstructed, he cannot readily grasp the slice being deflected and deposit it properly on the tray 52 while standing in the best position for operating the carriage 15. The gauge plate also has an extension 54 which extends 30 into close proximity with the circular guide 55 which is arranged over the cutting edge of the knife to the rear and above the same. With this arrangement, the knife is substantially guarded throughout its entire periphery during the slicing operation and while the gauge plate is in 35 operative position, thereby protecting the operator. When the slicing machine is not in use, the gauge plate can be moved so that its substance engaging surface is right in the cutting plane of the knife and while the gauge plate is in this position, it is practically impossible for the operator to be injured by the knife.

Obviously those skilled in the art to which this invention pertains may make various 45 changes in the construction and arrangement of the parts shown in the embodiment illustrated in the drawings without departing from the spirit of this invention, and therefore, I do not wish to be limited except as hereinafter set forth 50 in the claims.

Having thus fully described my invention, what I claim as new and desire to obtain by Letters Patent is:

1. A slicing machine comprising a support, a 55 knife, a gauge plate slidably mounted on said support with one edge thereof near the edge of said knife when in operative position, micrometer control means for actuating said gauge plate rectilinearly in a direction away from the cutting plane of said knife to move the substance engaging surface thereof through successive parallel positions, said control means being operable through variable increments of movement whereby to position said gauge plate in 60 various gauging positions with respect to the knife, said gauge plate being also movable in a plane parallel to its substance engaging portion when the gauge plate reaches a predetermined position of rectilinear adjustment, and means 65 for preventing said last mentioned movement of said gauge plate until the same reaches said position.

2. A slicing machine comprising a support, a 70 gauge plate slidably mounted on said support, an 75

- actuating member for sliding said gauge plate along said support, said actuating member being also operative to move said gauge plate in a plane perpendicular to the direction of its sliding movement to an inoperative position at which the same may be readily cleaned on continued actuation of said actuating member in the same direction as when moving said gauge plate along said support.
3. In a slicing machine, the combination with a slicing knife and a substance support movable relative to each other, a gauge plate having the substance engaging portion thereof arranged substantially parallel to the cutting plane of said knife, a slidable mounting for said gauge plate for moving said gauge plate to various positions parallel to the cutting plane of said knife and at varying distances therefrom, a portion of said slidable mounting normally preventing movement of said gauge plate in a direction parallel to the cutting plane of said knife in a plurality of the positions of adjustment thereof, said portion of said slidable mounting which normally prevents movement in a plane parallel to the cutting plane being out of operative position relative to said gauge plate when said gauge plate reaches a predetermined position of adjustment, whereby said gauge plate is thereafter movable in a plane parallel to the cutting plane of said knife to an inoperative position for cleaning purposes or the like, micrometer control means operable through various increments of movement for moving said slidable mounting, and graduated means for indicating the position of said micrometer means.
4. A slicing machine comprising a frame, a gauge plate, a rod secured to said gauge plate and rotatable and slidable within a bearing on said frame, means for moving said rod longitudinally of said bearing, and means normally preventing rotation of said gauge plate about the axis of said rod as a pivot except when said gauge plate is moved to a predetermined position of adjustment in the direction of the length of said rod, said last mentioned means comprising a pin on said frame extending parallel to said rod and having a portion thereof relatively slidable within an opening in said gauge plate while said gauge plate is being moved through certain positions of adjustment but being rendered inoperative when said gauge plate is in another of said parallel positions, whereby said pin is out of said opening, whereby said gauge plate can be moved about the axis of said rod as a pivot when said gauge plate is moved to said last mentioned position of adjustment.
5. A slicing machine comprising a frame having a bearing thereon, a rod slidable in said bearing and rotatable with respect thereto, a gauge plate secured to said rod, said rod extending beyond both ends of said bearing, said gauge plate being secured to one projecting end of said rod, and a feed-nut operatively connected to the opposite end of said rod, the rotation of said feed-nut causing said rod to be moved longitudinally of its bearing and having automatic self-locking means for locking the longitudinal feeding of said rod at a predetermined position of said gauge plate so that additional movement of said feed-nut will rotate said rod and move said gauge plate in a plane perpendicular to the axis of said rod.
6. A slicing machine comprising a frame having a bearing thereon, a rod slidable in said bearing and rotatable with respect thereto, a gauge plate secured to said rod, said rod extending beyond both ends of said bearing, said gauge plate being secured to one projecting end of said rod, and a feed-nut operatively connected to the opposite end of said rod, the rotation of said feed-nut causing said rod to be moved longitudinally of its bearing and having automatic self-locking means for locking the longitudinal feeding of said rod at a predetermined position of said gauge plate so that additional movement of said feed-nut will rotate said rod and move said gauge plate in a plane perpendicular to the axis of said rod.
7. A device as set forth in claim 5 in which the automatic self-locking connection comprises an abutment on said rod for limiting the relative movement of said rod and feed-nut in one direction, and a screw thread and cooperating projection on said rod and nut respectively whereby when said abutment moves against said feed-nut and is limited in its movement with respect thereto, said projection binds in the thread on said rod and the friction therebetween permits the operator to rotate the rod by rotating the feed-nut.
8. In a slicing machine, the combination with a slicing knife, of a substance support movable relative thereto, a gauge plate against which the substance on said substance support is moved to determine the thickness of the slice to be cut, a rod upon which said gauge plate is mounted, a bearing for said rod, said bearing and rod extending in a direction at a substantial angle to the cutting plane of said knife, and said rod being slidable longitudinally of said bearing, whereby to position said gauge plate in successive parallel positions, means for normally preventing rotation of said gauge plate about the axis of said rod when said gauge plate is in a number of said parallel positions, micrometer control means operable to various positions for actuating said rod in a direction longitudinally of its axis to move said gauge plate to any of said parallel positions in one of which said means which normally prevents rotation of said gauge plate about the axis of said rod occupies an inoperative position with respect to said gauge plate, whereby said gauge plate can be moved in a plane substantially perpendicular to the axis of said rod, and graduated means for indicating the position of said micrometer control means.
9. In a slicing machine, the combination with a slicing knife, of a substance support movable relative thereto, a gauge plate against which the substance on said substance support is moved to determine the thickness of the slice to be cut, a mounting for said gauge plate for constraining the movement of said gauge plate through successive positions parallel to the cutting plane of said knife and for holding said gauge plate against movement parallel to the cutting plane of said knife until said gauge plate reaches a predetermined position of adjustment in which the means which constrains the movement of said gauge plate in a direction parallel to the cutting plane of said knife occupies a position

- with respect to said gauge plate such that it is inoperative to prevent movement of said gauge plate in a direction parallel to the cutting plane of said knife, whereby said gauge plate is normally constrained to move through successive positions parallel to the cutting plane of said knife and is prevented from movement in a direction parallel to the cutting plane of said knife but is permitted at a predetermined position to have movement in said last mentioned direction so that it can be moved to a position remote from its operative position for cleaning purposes, and screw feed means for feeding said gauge plate through said successive positions.
10. A slicing machine comprising a frame, a slicing knife mounted in fixed relation to said frame, a gauge plate mounted on said frame by means of a slidable and rotatable connection therewith, the slidable connection permitting movement of said gauge plate through successive positions substantially parallel with the cutting plane of said knife and said rotative connection being such as to permit, when not otherwise restrained, movement of said gauge plate in a plane parallel to the cutting plane of said knife, actuating means and connections between said actuating means and said gauge plate for sliding said gauge plate along said frame, means to indicate the position of said actuating means, and means normally operative to prevent rotation of said gauge plate in a plane parallel to said cutting plane, while said gauge plate is in any one of a number of parallel positions, but being inoperative when said gauge plate is at another of said parallel positions, whereby said gauge plate may be rotated in a plane parallel to the cutting plane of said knife to a position remote from the cutting edge of said knife.
15. 11. A slicing machine comprising a frame, a slicing knife mounted in fixed relation to said frame, a gauge plate mounted on said frame by means of a slidable and rotatable connection therewith, the slidable connection permitting movement of said gauge plate through successive positions substantially parallel with the cutting plane of said knife and said rotative connection being such as to permit, when not otherwise restrained, movement of said gauge plate in a plane parallel to the cutting plane of said knife, means for sliding said gauge plate along said frame, and means normally operative to prevent rotation of said gauge plate in a plane parallel to said cutting plane, while said gauge plate is in any one of a number of parallel positions, but being inoperative when said gauge plate is at another of said parallel positions, whereby said gauge plate may be rotated in a plane parallel to the cutting plane of said knife to a position remote from the cutting edge of said knife, said 20 means comprising a pin slidable in an opening in said gauge plate, the axis of the opening being eccentric with respect to the center of pivotal movement of said gauge plate, and said pin being rendered inoperative when said gauge plate is moved to another position of adjustment in which said pin is out of said opening, at which latter position of adjustment of said gauge plate, said gauge plate can be rotated about its pivotal center.
25. 12. A slicing machine comprising a frame having a bearing therein, of a slicing knife, a gauge plate having the operative surface thereof substantially parallel to the cutting plane of said knife, a rod extending at a substantial angle to the cutting plane of said knife and secured to
- said gauge plate, said rod being mounted for sliding and rotating movement in said bearing, control means movable in a given manner and through given limits of movement for moving said rod longitudinally of said bearing, and means normally preventing rotation of said rod in said bearing except when said gauge plate is moved to a predetermined position of adjustment in the direction of the length of said rod, said control means being movable in the same manner but through greater limits of movement to rotate said rod.
30. 13. In a slicing machine, the combination with a frame, of a slicing knife mounted in substantially fixed relation with respect to said frame, said frame having a bearing therein extending substantially perpendicular to the cutting plane of said knife, a rod rotatably and slidably mounted in said bearing, a gauge plate secured to said rod for movement therewith, a second rod secured to said frame and having a slidable connection with said gauge plate for guiding said gauge plate as the same is moved with said rod and for preventing rotation of said gauge plate about the axis of said rod in most of the positions of said gauge plate, but being inoperative in one position of said gauge plate for preventing rotation of said gauge plate about said axis in one direction due to the movement of said gauge plate to a position in which a portion of said slidable connection is rendered inoperative.
35. 14. In a slicing machine, the combination with a frame having a bearing therein, a rod rotatable and slidable in said bearing, a second rod secured to said frame having a portion thereof slidable within a bearing on said gauge plate, which bearing embraces said portion sufficiently to prevent movement of said gauge plate transversely to said second rod, in a multiplicity of positions of said gauge plate, said gauge plate being movable to a position in which said portion of said second rod is out of said bearing, and a projection on said gauge plate for engaging said portion of said second rod after that portion is out of said bearing in said gauge plate for preventing rotative movement of said gauge plate in one direction but being inoperative to prevent rotation thereof in the opposite direction, whereby upon rotative movement of said first rod, said gauge plate can be moved in a plane perpendicular to the axis of said rod.
40. 15. A slicing machine comprising a frame having a bearing thereon, a rod slidable in said bearing and rotatable with respect thereto, a gauge plate carried by said rod, means for advancing said rod in the direction of its length, and means operable upon longitudinal movement of said rod to a predetermined position for locking said advancing means to said rod to prevent relative rotation therebetween, whereby continued motion of said advancing means causes rotative movement of said rod and said gauge plate.
45. 16. A device as set forth in claim 15 which includes in addition, means for positively restraining rotative movement of said gauge plate in a direction perpendicular to the axis of said rod substantially until the said rod reaches the position at which said advancing means is locked in position with respect to said rod.
50. 17. A slicing machine comprising a frame having a bearing thereon, a rod slidable in said bearing and rotatable with respect thereto, a gauge plate carried by said rod, means for ad-

vancing said rod in the direction of its length, and means operable upon longitudinal movement of said rod to a predetermined position for locking said advancing means to said rod to prevent relative rotation therebetween, whereby continued motion of said advancing means causes rotative movement of said rod and said gauge plate, said means for locking said advancing means to said rod comprising 5
10 an abutment on said rod for engaging said advancing means, and a cam engaging means on said advancing means for forcing said advancing means firmly against said abutment whereby continued movement of said advancing means 15 causes said rod to rotate therewith.
18. A slicing machine comprising a frame member, a gauge plate member, a rod secured to said gauge plate member and rotatable and 20
25 slidable within a bearing on said frame, means for moving said rod longitudinally of said bear-

ing, and means normally preventing rotation of said gauge plate member about the axis of said rod as a pivot except when said gauge plate member is moved to a predetermined position of adjustment in the direction of the length of said rod, said last mentioned means comprising a pin relatively positioned between the gauge plate member and the frame member extending parallel to said rod and having a portion thereof relatively slidable within an opening in one of 10 said members while said gauge plate member is being moved through certain positions of adjustment but being rendered inoperative when said gauge plate member moves to another position in which said pin is out of said opening, whereby 15 said gauge plate member can be moved about the axis of said rod as a pivot when said gauge plate member is moved to said last mentioned position of adjustment.

JOSEPH FOLK. 20
